Attns.

UNITED STATES PATENT OFFICE.

JAMES FATKIN, OF GULCH, COLORADO.

WRENCH.

SPECIFICATION forming part of Letters Patent No. 663,163, dated December 4, 1900.

Application filed April 25, 1900, Serial No. 14,244. (No model.)

To all whom it may concern:

Be it known that I, JAMES FATKIN, a citizen of the United States, residing at Gulch, in the county of Pitkin and State of Colorado, have 5 invented certain new and useful Improvements in Wrenches; and I do hereby declare the following to be a full, clear, and exact description of the invention, such as will enable others skilled in the art to which it appertains 10 to make and use the same.

My invention relates to certain new and useful improvements in wrenches for pipes, tubes, rods, nuts, and the like, and is designed to provide a construction of strength and stability, of a comparatively few number of parts, and which may be readily manipulated to grasp or release the object to which it is applied at the will of the user.

In the accompanying drawings, Figure 1 20 represents a side elevation of a wrench embodying my improvements, the handle being shown as partly broken away. Fig. 2 represents a front elevation thereof, partly in section. Fig. 3 represents in perspective the 25 swinging nut upon which the movable jaw of the wrench is adapted to rock.

Similar letters of reference indicate similar parts through the several views.

Referring to the drawings, A indicates the 30 wrench-handle provided with a fixed jaw arranged at a predetermined angle to the handle and having preferably a serrated face a. At a suitable location along the length of the handle are located the cheek-pieces b b', which 35 serve as guides for the movable jaw of the wrench and as bearings for a nut having a limited rocking motion or swing, as will hereinafter more fully appear. The movable jaw has preferably an inclined clamping-face c 40 and is provided with a longitudinal slot d, extending throughout its main body portion. The outer end e of the movable jaw is provided with a cylindrical aperture and is provided with a movable screw-threaded pin f, 45 which is adapted to engage within a groove g of a feed-screw B in such manner as to permit the rotation of the screw, but to hold it against longitudinal movement relative to the movable jaw itself. The screw B is provided with a milled or knurled head C at one 50

end, and at the other end, h, is rounded, as shown, so as to fit within a recess provided for the purpose. The screw B passes through an internally - screw - threaded nut, (shown separately in Fig. 3,) wherein k indicates the 55 internally-screw-threaded aperture of the nut. The nut is provided with trunnions or journals l m at its opposite ends, one of said trunnions or journals being of lesser diameter than the other and the nut being flattened 60 on both sides between the said trunnions or journals. The cheek-pieces b b' are provided with apertures or journal - bearings corresponding to the diameter of the trunnions l m, respectively, the arrangement being such 65 as to permit the slight rocking movement desired for securely clamping or releasing the object grasped by the wrench.

The parts of the wrench may be assembled with great facility, this feature constituting 70 a characteristic advantage of the construction shown. Thus, the movable jaw is first placed between the cheek-pieces, whereupon the nut of Fig. 3 is dropped into place and necessarily adjusts itself in suchwise that 75 aperture k is in exact alinement with the aperture of the end e of the movable jaw. This alinement is insured by the fact that the sides of the nut are guided by the proximate sides of the slot d and that the shoulders n exactly limit the manner in which the nut seats itself in the cheek-pieces. The aperture k being in the alinement referred to the operator thereupon inserts the screw B and locks the screw against longitudinal 80 movement by inserting the screw-pin f.

The operation of the invention will be apparent. By turning the milled or knurled head C the movable jaw will be caused to advance until the object to be turned is clamped 90 between the fixed face a and the movable face c. By turning the handle in the one direction or the other, as the case may be, the tube, rod, or other object is either firmly grasped by a slight inward rocking movement 95 of the movable jaw or is instantly released by a correspondingly-slight outward rocking movement thereof. In this movement the nut rocks upon its trunnions to the light extent desired, and the stress or strain put upon 100

the parts is communicated to the screw B and through it to the nut and thence to the stout cheek-pieces of the stationary jaw.

Having thus described my invention, what I claim is—

1. A wrench, comprising a handle having a fixed jaw, a longitudinally-slotted movable jaw adapted to travel toward and from the fixed jaw, a nut traversing the movable jaw 10 transversely through the slot, said nut being provided with trunnions one of which is larger than the other, cheek-pieces projecting from the wrench-handle and having apertures or journal-bearings corresponding respectively to the trunnions, and a feed-screw passing 15 to the trunnions, and a feed-screw passing through said nut and receiving the thrust of the movable jaw; substantially as described.
2. A wrench, comprising a handle having a fixed jaw, a longitudinally-slotted movable

jaw adapted to travel toward and from the 20 fixed jaw, a nut traversing the movable jaw transversely through the slot, said nut being provided with trunnions one of which is larger than the other, and having flattened sides between said trunnions corresponding to the 25 width of the slot of the movable jaw, cheek-pieces projecting from the wrench-handle and having apertures or journal-bearings corresponding respectively to the trunnions, and a feed-screw passing through said nut and 30 receiving the thrust of the movable jaw; substantially as described.

In testimony whereof I affix my signature in presence of two witnesses.

JAMES FATKIN.
